UNITED STATES PATENT OFFICE.

RALPH W. HUTCHENS, OF EAU CLAIRE, WISCONSIN, ASSIGNOR TO GILLETTE RUBBER COMPANY, OF EAU CLAIRE, WISCONSIN, A CORPORATION OF WISCONSIN.

DESIGN FOR A TIRE TREAD OR A SIMILAR ARTICLE.

Application filed December 1, 1924. Serial No. 11,546. Term of patent 14 years.

To all whom it may concern:

Be it known that I, RALPH W. HUTCHENS, a citizen of the United States, residing at Eau Claire, Eau Claire County, Wisconsin, have invented a new, original, and ornamental Design for a Tire Tread or a Similar Article, of which the following is a specification, reference being had to the accompanying drawing, forming part thereof.

I claim:

The ornamental design for a tire tread or a similar article, as shown.

RALPH W. HUTCHENS.
